UNITED STATES PATENT OFFICE.

FRED BOLD, OF ST. LOUIS, MISSOURI, ASSIGNOR OF ONE-HALF TO WILLIAM M. STANTON, OF SAME PLACE.

LUBRICATOR.

SPECIFICATION forming part of Letters Patent No. 325,904, dated September 8, 1885.

Application filed May 1, 1885. (No model.)

To all whom it may concern:

Be it known that I, FRED BOLD, of the city of St. Louis, in the State of Missouri, have invented a certain new and useful Improvement 5 in Lubricators, of which the following is a full, clear, and exact description, reference being had to the accompanying drawings, forming part of this specification.

Figure 1 is a side view of the lubricator 10 with part of the screw-cap broken away. Fig. 2 is a vertical section at 2 2, Fig. 1. Fig. 3 is a transverse section at 3 3, Fig. 2. Fig. 4 is a transverse section at 4 4, Fig. 2. Fig. 5 is a transverse section at 5 5, Fig. 2, with the 15 valve removed.

This lubricator belongs to the class in which water resulting from the condensation of the steam within the lubricator causes the overflow of oil into a discharge-tube.

20 The body of the lubricator is shown as cast in one piece; but I do not confine myself to this construction.

A is the oil-cup, and B the oil-chamber.

25 C is a screw-threaded nipple, by which the lubricator is secured to the steam-chest, cylinder, or other object.

D is a tube extending upward from the bottom of the cup, and having at top a conical valve-seat, E, the bore F of the tube extending down through the nipple C.

30 G is the tubular neck of the cup, which has interior and exterior screw-threads. The valve H is formed to fit the seat E. Its stem I has a screw-threaded part or collar, J, working in the female screw of the neck, and an angular top, K, to which an adjusting key or wrench is applied to raise or lower the valve.

35 L is a jam-nut, which also works in the female screw of the neck G, and which serves to hold the valve to its adjustment, the bottom of the nut bearing upon the top of the collar J.

M is the angular part of the jam-nut, to which the wrench or key is applied to turn it.

40 N is the screw-cap, which turns on the male screw of the neck G, and which has at bottom an annular rim or flange, O, bearing, when the cap is screwed down, upon the soft-metal seat P, which is cast in an annular dovetail recess, Q, made in the top of the oil-cup. I prefer to 45 form the recess or groove Q wide enough to

allow the annular rim or flange O to enter the recess as the soft metal wears away.

At the upper end of the screw-cap N is a steam-condensing chamber, R, into which the steam is allowed to enter from the oil-chamber 55 B, and from which the water of condensation returns to the chamber and raises the surface of the oil and causes it to overflow the upper end of the tube D. As a means for this passage of steam and water, I show a vertical 60 groove, S, cut in the inner side of the neck G, and a passage, T, extending through the collar J and communicating with an annular passage at U between the jam-nut and the valve-stem. Either or both these means of communication between the oil-chamber and condensing-chamber may be used, or equivalent means for these purposes.

5 V are orifices in the sides of the neck, through which the oil is poured in when the cap has 70 been raised a small distance, the filling of course being done when there is no steam-pressure within the oil-chamber.

W is the waste-pipe, having at the mouth a counter-bore, X, and within that a female screw, 75 Y, in which works the tubular stem Z of the plug, by which the mouth of the drain-passage is closed. The face of the flange b of the plug is formed with an annulus, a, of soft metal run into a dovetail annular groove of the 80 flange-head b. The annular plug-seat c is preferably made so thin as to enter the dovetail groove containing the soft-metal facing as the metal of the facing wears away.

85 d is an aperture in the side of the tubular stem to allow the escape of liquid from the oil-cup when the plug is opened by turning out the valve stem a short distance.

It will be seen that as in discharging it is not necessary to remove the plug-stem Z from 90 the discharge-mouth, so it is not needed in filling the oil-chamber to remove the cap N from the neck G, it being only necessary to remove the cap to allow adjustment of the valve H.

95 I claim—

1. The combination of an oil-cup formed with a screw-threaded neck, G, having an orifice, V, in its side, a seat having a recess surrounding said neck, a soft-metal filling in said 100

recess, and a cap, N, having an interior screw-thread by which it is secured to said neck, and a rim or flange, O, bearing on said filling, substantially as set forth.

5. 2. The combination of an oil-cup formed with a dovetail annular recess, Q, and a screw-threaded neck, G, having an orifice, V, in its side, a soft-metal seat occupying said recess, and a cap, N, screwing on said neck, and having a flange or rim, O, seating on said seat, substantially as set forth.

3. The combination of an oil-cup formed with an interiorly screw-threaded neck, G, a valve, H, having a stem, I, formed with a screw-threaded portion, J, within the neck G, and a tubular jam-nut, L, seating on said portion within said neck, substantially as set forth.

4. The combination of an oil-cup formed with a waste-pipe, W, having a counter-bore, X, at the mouth, and interior screw-thread, Y, and a hollow plug, Z, having a flange, b, closing said pipe and orifice d, substantially as set forth.

5. The combination of an oil-cup formed with a waste-pipe, W, having a seat, c, counter-bore X, and interior screw-thread, Y, and the hollow plug Z, having a flange, b, formed with a dovetail recess provided with a soft-metal filling, a, screw-thread, and orifice d in said screw-thread, substantially as set forth.

FRED BOLD.
